(57) **CLAIM**

The ornamental design for a multi-compartment animal shelter, as shown and described.

DESCRIPTION

FIG. 1 is a front perspective view of a multi-compartment animal shelter;

FIG. 2 is a front view of the multi-compartment animal shelter of FIG. 1;

FIG. 3 is a back view of the multi-compartment animal shelter of FIG. 1;

FIG. 4 is a top view of the multi-compartment animal shelter of FIG. 1;

FIG. 5 is a bottom view of the multi-compartment animal shelter of FIG. 1;

FIG. 6 is a first side view of the multi-compartment animal shelter of FIG. 1;

FIG. 7 is a second side view of the multi-compartment animal shelter of FIG. 1;

FIG. 8 is a front perspective view of the multi-compartment animal shelter of FIG. 1 in an opened position;

FIG. 9 is a top view of the multi-compartment animal shelter of FIG. 8;

FIG. 10 is a cross-sectional view of the multi-compartment animal shelter taken along line 10-10 of FIG. 8;

FIG. 11 is a cross-sectional view of the multi-compartment animal shelter taken along line 11-11 of FIG. 8; and,

FIG. 12 is a cross-sectional view of the multi-compartment animal shelter taken along line 12-12 of FIG. 8.

The multi-compartment animal shelter is shown with a symbolic break in its length. The appearance of any portion of the article between and including the break lines forms no part of the claimed design.

The broken lines shown in the drawings illustrate portions of the multi-compartment animal shelter that form no part of the claimed design. The broken cross-sectional arrows shown in FIG. 8 form no part of the claimed design.
